APPARATUS FOR FORMING WELL SCREENS

Application filed October 12, 1925. Serial No. 62,190.

This invention relates to an apparatus for forming well screens, the casing screen being of the type employed in water, gas or oil wells to prevent sand or other débris entering the well with the water or oil.

Hitherto, the art has had considerable difficulty in providing a proper screen for well use. It is necessary that screen to be employed in well use should possess considerable resistance to collapsing, since it frequently is subjected to considerable hydraulic pressure upon its outer side and moreover the walls of the well may at times cave in upon the screen. It is also necessary to obtain the proper results that the openings of the screen should be of uniform size and produced without cutting away more material from the casing than is necessary to form the opening or without otherwise weakening the casing. It is also desirable that the openings of the screen should be of minimum size at the exterior of the screen and that the openings of the screen should expand or enlarge at least slightly inwardly in order that the openings will not become clogged. It is also desirable to form a well screen with smooth exterior and interior surfaces, so that the screen when being lowered in place or otherwise will not catch against the formations or be otherwise substantially worn, and so that there is no projection on the inside to catch or wear a swab or other thing lowered or pulled from the well.

Attempts have been made to form well screen openings by milling a tube casing from the inside. Said processes remove so much material from the inner side of the well screen that the screen casing is very weak and easy to collapse. The art has also attempted to provide the proper screen openings by forming them separate from the tube or casing in the form of a button or plug which is later screw-threaded or otherwise affixed to a larger opening in the screen tube. This method not only produces a screen weak where the buttons are connected to the tube, but involves considerable expense. The art has attempted to form well screen openings by initially punching or milling the screen from the outside and then punching the wall

adjacent the openings so produced to crimp the wall over and produce the minimum size opening at the outside and regulate the size of the outer opening. This leaves the screen weak at the perforations and destroys the smooth exterior of the casing.

It is an object of the present invention to provide an apparatus for forming well screen by which screen is produced in one integral piece and provided with openings of uniform size at a relatively low cost without any substantial roughening of the exterior or interior of the casing and at the same time so treating the material around the screen openings as to strengthen the screen at the openings and thus provide both an improved form of well screen in regard to smooth exterior and interior surfaces and character and uniformity of screen openings, and to provide a well screen of greater strength against collapsing than those now in use.

It has been found that by forming well screen openings in a casing or tube by the use of a punch and die the screen openings may be readily brought to a uniform size. Moreover, by actuating the punch from within the casing to the form of openings, these openings may be formed with a minimum removal of material from the casing and also with an accompanying action upon the casing or walls of the casing surrounding the opening highly beneficial to the finished screen.

In carrying out the punching operation, the punch is cold pressed in the screen from the inner side, the punch being provided with tapering walls which force part of the material which previously occupied the opening into the screen wall, strengthening the same by cold pressing operation. The treatment of casing in this manner required the utilization of great forces in order that the cold metal will properly assume the desired form. Moreover, these forces must be properly and accurately regulated so that simultaneously with the requisite punching force applied to the punching, a die is placed against the outer screen wall in alignment therewith. The force applied to the punch

must be caused to be applied within the casing or tube which may be of considerable length.

The invention improves the provision of an apparatus for the regulation and transmission of these forces and for their proper direction against the work.

The invention also provides an apparatus adaptable to forming other apparatus for well use such as well casing in which a tube or casing is desired to be acted upon from its inner side for either the forming of openings or removing or distorting material from the walls of the casing into regulated positions.

Various other objects and advantages of the preferred invention will appear from the description of an apparatus embodying the invention and from a description of the products which may be formed by such method and apparatus. For this purpose reference is made to the accompanying drawings, in which a preferred form of well screen is illustrated and a preferred apparatus by the use of which a preferred method may be carried out.

Referring to the drawings:

Figure 1 is a front elevation of the apparatus partially in section and horizontally broken to shorten the view,

Fig. 2 is an end elevation,

Fig. 3 is an enlarged elevation partially in section of the tool or punch head.

Fig. 4 is a section on the line 4—4 of Fig. 3,

Fig. 5 is a further enlargement of the tool or punch head, the view being in vertical section and illustrating the action of the tool upon a casing against which a die is placed.

Fig. 6 is a section on the line 6—6 of Fig. 5,

Fig. 7 is a view similar to Fig. 6 with the tool and die illustrated in the retracted position.

Fig. 8 is a cross section of a well screen formed by the apparatus.

Fig. 9 is a perspective of the tool head holding one end of the casing enclosing the tool actuating shaft,

Fig. 10 is a perspective of a guide block forming part of the tool head,

Fig. 11 is an enlarged transverse section of the tool and die with a section of casing therebetween.

Fig. 12 is a side elevation of a modified form of punching apparatus, the view being partially in vertical section,

Fig. 15 is a section on the line 15—15 of Fig. 13.

Fig. 16 is a section on the line 16—16 of Fig. 13.

Fig. 17 is a section on the line 17—17 of Fig. 13.

Fig. 18 is a section of a tool head of modified form for use in connection with the apparatus of Figs. 1 to 11, inclusive, when it is desired to form casing for well use.

Fig. 19 is a side elevation of a section of well screen.

Referring to the drawings, the apparatus preferably comprises a punch press 2 which should be of considerable size and may be of various desired forms. The press is provided with a horizontal shaft 3 carrying a cam or other means for reciprocating a vertically guided ram 4 from a connecting rod 5 as the shaft 3 is rotated. One end of the shaft 3 is indicated as terminating in means such as a gear wheel 6 by which power may be supplied to the apparatus from any desired means not shown. The lower end of the reciprocating ram 4 is provided with a socket carrying a die 7. The die 7 is provided with a horizontal groove 8 to conform with the exterior surface of the casing or other work to be acted upon and also with a short tip to cooperate with a relatively longer tip or end of a punch or other tool 10 when their members are at the end of the punching stroke of the apparatus.

The base 11 of the press supports a horizontally grooved casing rest 12 shaped to conform with the exterior surface of casing or other work to be acted upon by the apparatus.

Positioned at one side of the punch press 2 is placed a foot stock or pedestal 13 at a distance somewhat over half the length of the casing or pipe to be operated upon by the apparatus, the foot stock or pedestal carrying a bearing 14 for supporting the continuation of the horizontal shaft 3. The shaft 3 extends through the bearing 14 and is provided at its end with a cam 15. The cam 15 engages a roller 16 carried by one arm 17 of a lever 18. The lever has another arm 18^a supporting a weight 18^b.

The lever 18 is rigidly mounted upon a horizontal punch actuating shaft 19 which extends to a point between the casing rest 12 and die 7. Shafts 3 and 19, together with lever 18 are made of heavy solid stock so that any movement of shaft 3 is positively imparted to shaft 19.

The shaft 19 is through the greater portion of its length enclosed by a horizontal casing 20, one end of which is screwed into the foot stock or pedestal 13 as indicated at 21 and there provides a bearing for the shaft 19. The other end of the casing 20 extends to near the end of the shaft 19 and there provides a second bearing 22 for the shaft.

As most clearly illustrated in Figures 6

and 7 of the drawings, the end of the shaft 19 under the die 7 is longitudinally bored from its end to accommodate three small rollers 23 and accommodate a large roller 24 mounted by the three small rollers 23. The roller 24 has about half its diameter extending beyond the normal exterior surface of the shaft 19.

10 indicates a tool member having a depending body part 26 abutting the end of the shaft 19 and provided with a curved groove 26^a receiving a pin 28 near the lower end of the shaft 19. The tool member 10 is also provided with a body portion 27 extending over the end of the shaft 19 having a flat end face 29 and flat vertical sides 30. The tool member 10 is provided with a tool head 31. In the form of the invention illustrated in Figs. 1 to 11, inclusive, this head 20 is indicated as in the form of a punch preferably of the kind adapted to form a slit longitudinally in a well casing, the tip 33 of the punch being indicated as tapered.

The end of the casing 20 enclosing the shaft 19 is closed as indicated at 34, and provided with an upper opening 35 fitting the upper body part 27 of the tool member 10 and thus guiding said member so that it is confined to a vertical reciprocating movement. Below the opening 35 the casing 20 is also cut away as indicated at 36 (best shown in Fig. 9) and the bearing 22 is enlarged as indicated at 37, in order to extend slightly below the casing 20 and engage the lower inner wall of the casing A to be operated on. The enlargement 37 is cut away at its upper end 38 to fit the casing 20 (see Figs. 6 and 7).

The tool member 10 has its part 27 normally engaging the large roller 24 carried by 40 the tool operating shaft 19. At one side of the end of the shaft 19 adjacent the roller 24, the shaft is flattened as indicated at 39 to support the tool member 10 when the shaft is rotated or oscillated to lower the tool 45 head (see Fig. 7). It is thus seen that by oscillation of shaft 19 from the retracted position of Fig. 7, where the tool member is resting against the flat face 39, to the position of Fig. 6, where the tool head is forced 50 into the uppermost position by riding upon the roller 24, the tool head can be reciprocated to act upon the inner side of the casing A, forming screen openings therein or performing other desired operations. The 55 roller 24 acts as a cam on the tool member 10 and permits the direction of large forces against the inner wall of casing A.

The end 34 of the casing 20 receives a connection 40 communicating with a duct 41 60 therein, which duct is adapted to register with a similar duct 42 in the body part 26 of the tool member, in one position, so that lubricant may be supplied from connection 40 to the rollers 23 and 24 carried by the 65 shaft 19.

The operation of the apparatus and the method operating upon the casing may now be described:

The casing A which is to be operated upon, in this example to be perforated to form well screen, is first slipped over the casing 20 carrying the tool head and permitted to rest against the casing rest 12, the weight of the end of the tool head being supported likewise against said rest through the casing A. Power is then supplied to rotate the shaft 3 by means connected with the gear wheel 6. The rotation of the shaft 3 causes the die 7 to be alternately presented or pressed against the exterior surface of casing A and retracted therefrom. At each time the die 7 is presented to the exterior surface of casing A, the tool member is actuated to operate upon the screen and during each retraction of the die 7, the casing A is shifted to a new position, either by mechanical means not shown or through manual operation. Part of the power applied to the shaft 3 is transmitted longitudinally through the casing A to be perforated, in order to force the head of the tool member against the casing A opposite the die 7, where such tool member 10 may move material from its normal position in the casing wall against the die 7 producing a resulting effect upon the casing A dependent upon the shape of the die 7 and head of the tool member 10. The transmission of this force is through the rotation of shaft 3 and cam 15 depressing arm 17 of lever 18 when die 7 is lowered against the wall of the casing A. Such lowering of arm 17 oscillates shaft 19 to ride tool member 10 upon roller 24, pressing the head of the tool member against the casing, the reaction of the casing A to such advance of the tool member being received upon the rest 12.

As the tool member 10 reaches its uppermost position and the die 7 is firmly pressed against the exterior surface of casing A, cam 15 is rotated to a position where it permits lever 17 to rise again under the influence of weight 18^b. This retracts the tool member from the casing and permits the casing A to be shifted to a second position.

When it is desired to form well screen openings and the tool member and die are of the described form, this operation produces elongated slots in the pipe closed by a slight web 32 which is later milled out and with a smooth exterior surface. The material of the casing A in front of the tapered tip 33 of the tool head or punch is forced outward, consolidating the structure of the casing around the opening and materially strengthening the same. Preferably the die 7 is actuated through a relatively longer stroke than the punch so that the punch will be forced to its most advanced or upward position in advance of the corresponding or down stroke of the die member. The result-

ing effect is that the casing being operated upon, not being positively confined against movement when the punch is pressed thereagainst, bulges slightly outward as the punch 5 assumes its most upward position with the punch cutting substantially into the wall of the casing; the die then descends against the casing, pressing or ironing out the bulge and forcing the punch to cut into the casing and 10 press the material in front of the punch laterally into the walls of the casing. In this manner, the greater force for the actual punching operation does not have to be applied to actuate the punch, but in place thereof this force can be applied to die work without the casing.

In this manner, the casing is perforated without substantially roughening or weakening of the adjacent walls of the casing and 15 openings of uniform size are produced, accompanied by a consolidation of the material around the opening which materially strengthens the resulting well screen.

The apparatus just described is adapted 20 not only for the production of an improved well screen, but for the production of various different products. For example, as illustrated in Fig. 18, by modifying the head of the tool member 10 so that it is provided 25 with a rounded point 33^a and replacing the die 7 with a die 7^a having a concave depression 8^a, the apparatus is capable of use in heading or embossing lapped casing for well use.

In the formation of such casing, it is necessary to join two lapped sections of casing rigidly together by some suitable means, these casings being indicated at B and C in Fig. 18. These casings are placed as indicated over the end of the tool head and the apparatus actuated so that the die 7^a is presented against the exterior of the outer casing 7 simultaneously with the forcing of the tool member 10 against the inner wall of the casing B so that the rounded head 33^a of the tool member forces the material of casings B and C outwardly from their original position, the final form assumed by such material being regulated by proper confining action of the die 7^a so that the casings are upset one in the other and rigidly interlocked.

The invention may be embodied in various forms, of which Figs. 12 to 17 indicate a second embodiment, similar parts in these figures being indicated by similar reference characters. In place of employing a cam 15, the embodiment of Figs. 12-17 is provided with a large gear wheel 15^a on the shaft 3. Said gear wheel is in engagement with a gear wheel 18^a on the shaft 19. The shaft 19 carries a punch head of modified construction adapted to reciprocate a tool head 49 in a vertical direction by a continual rotation of the shaft 19. For this purpose, the shaft 19 is provided adjacent the press 2 with two

similar spaced-apart eccentric surfaces 45 and 46, and with an eccentric surface 47 between the surfaces 45 and 46, the surface 47 having its furthermost radial point in a direction opposite to the furthermost radial points of the surface 45 and 46. The casing 20 is provided with an opening 48 in its upper side to receive the tool member 49 fitting the walls of the opening and it is guided thereby in a vertical direction, the tool member terminating in a tool head of desired form, such as a punch. This opening and tool member are arranged in position so that the tool member 49 rides upon the central eccentric surface 47 and the lower seat of the 75 casing 20 is provided with two similar openings 51 and 52 respectively, below the surfaces 45 and 46 respectively, for receiving and guidably supporting bearing shoes 53 and 54 respectively, having their lower surface shaped to conform with the interior surface of the casing to be operated upon.

The operation of this form of the apparatus is as follows:

The casing A to be operated upon is first 90 slipped over the casing 20 carrying the tool head and permitted to rest against the casing rest 12, as with the previous embodiment of the invention. Power is then applied to rotate shaft 3 by means connected with wheel 95 6. The rotation of the shaft 3 causes the die 7 to be alternately presented or pressed against the exterior surface of casing A and retracted therefrom. At each time the die 7 is presented to the exterior surface of casing 100 A the tool member is actuated to press the punch or tool head 50 against the upper inner wall of casing A, forcing material therefrom into position determined partly by the shape 105 of the punch and the confining action of the die 7.

The requisite force for this operation is imparted from the unit source of power through shaft 3 and gears 15^a and 18^a where, by rotation of shaft 19, the eccentric surfaces 45, 46 and 47 reciprocate the tool head 49 in synchronism with the presentation and retraction of die 7 against the exterior casing A.

While the same form of punch and die may 115 be used in this embodiment of the invention as was described in connection with Figs. 1-11 inclusive, I have shown a modified form. In the embodiment illustrated in Figs. 12-17 inclusive, the tapered punch is actuated 120 through a stroke sufficient to pierce entirely through the casing A and the die is provided with an opening to receive the tip of the punch. The result of the method and operation is to form narrow slits in the casing A 125 with rough projecting edges. These edges are then removed as by filing to form a finished screen with a smooth exterior surface.

By the apparatus herein described, well 130 screen of improved form may be provided.

It is pointed out that use of the jointly actuating punch and die members produce openings, the walls of which have been cold pressed and thus hardened. The cold 5 pressed walls of the casing adjacent the openings prevent the formation of the screening openings from weakening the casing which is as strong or stronger after the punching operation as before such operation.

10 While the embodiments of the invention herein illustrated are well adapted for accomplishing the objects of the invention, it is understood that various modifications may be made in the details of construction and arrangement of parts without departing substantially from the spirit of the invention, and the invention is not therefore limited to the specific form described for the purposes of illustration, but includes all such modifications as come within the scope of the appended claims.

I claim:

1. In an apparatus of the class described, a punch press having a base, a die mounted 25 on the press in a position to be alternately presented and retracted from a casing supported on the base of the press, a foot-stock, a horizontally disposed casing having one end supported by the foot-stock and the other 30 end extending between the base and the die of said press, said casing supporting a tool in position to cooperate with said die, an actuating shaft for the tool extending through said casing, and connecting means 35 between said die and shaft for simultaneously actuating the die and tool.

2. In an apparatus for perforating well casing, a punch press, a die vertically guided by the press, an operating shaft provided 40 with means for reciprocating the die upon its rotation, a foot-stock, a horizontally disposed casing having one end supported by the foot-stock and the other end extending to the press, a punch guidably mounted on the casing in 45 position to cooperate with said die, an actuating shaft for the punch extending through said horizontal casing and supported at one end by said foot-stock, the die actuating shaft extending to said foot-stock and provided 50 with connecting means with said punch actuating shaft, whereby rotation of said die actuating shaft actuates the punch and die in unison.

3. In an apparatus of the class described, 55 a punch press, a die mounted by the press and adapted to be alternately presented and retracted from a casing supported on the base of said press, means adapted to extend into said casing and supporting a punch in position to co-operate with said die, means for reciprocating the punch within said casing, and connecting means between said die and punch for operating the same together, said punch being adapted to occupy its punching 65 position in advance of the engagement of the

die with the casing, whereby the punch first causes a part of the casing surface to bulge outwardly and then the die engages said bulging surface to iron the same out on the punch and cause the punch to cut into the 70 casing.

Signed at Los Angeles, California this 17 day of September, 1925.
